US00D941395S

(12) **United States Design Patent** (10) **Patent No.:** **US D941,395 S**
(45) **Date of Patent:** **** Jan. 18, 2022**

(54) **PERIPHERAL DEVICE CONNECTOR**

(71) Applicant: **Nintendo Co., Ltd.**, Kyoto (JP)

(72) Inventors: **Yui Ehara**, Kyoto (JP); **Yuko Zenri**, Kyoto (JP); **Junichiro Miyatake**, Kyoto (JP); **Tetsuya Akama**, Kyoto (JP); **Hitoshi Tsuchiya**, Kyoto (JP)

(73) Assignee: **NINTENDO CO., LTD.**, Kyoto (JP)

(**) Term: **15 Years**

(21) Appl. No.: **29/747,773**

(22) Filed: **Aug. 25, 2020**

Related U.S. Application Data

(62) Division of application No. 29/645,459, filed on Apr. 26, 2018, now Pat. No. Des. 897,437, which is a division of application No. 29/595,213, filed on Feb. 27, 2017, now Pat. No. Des. 819,696.

(57) **CLAIM**

The ornamental design for a peripheral device connector, as shown and described.

DESCRIPTION

FIG. 1 is a front side perspective view of a peripheral device connector showing our new design;

FIG. 2 is a back side perspective view thereof;

FIG. 3 is a front view thereof;

FIG. 4 is a back view thereof;

FIG. 5 is a top view thereof;

FIG. 6 is a bottom view thereof;

FIG. 7 is a right view thereof;

FIG. 8 is a left view thereof; and,

FIG. 9 shows a back side perspective view of the peripheral device connector of FIG. 1 in an alternate position with a stand extended.

The broken lines in FIGS. 1-9 show example environmental structure and form no part of the claimed design.

1 Claim, 7 Drawing Sheets
